A. S. SPIEGEL.
APPARATUS FOR PRODUCING SHINGLES.
APPLICATION FILED JUNE 18, 1917.
1,260,088. Patented Mar. 19, 1918.

Inventor:

Alexander S. Spiegel,
by Spear Middleton Deacon & Spear,
Atty's.

UNITED STATES PATENT OFFICE.

ALEXANDER S. SPIEGEL, OF CHICAGO, ILLINOIS.

APPARATUS FOR PRODUCING SHINGLES.

1,260,088.

Specification of Letters Patent. Patented Mar. 19, 1918.

Application filed June 18, 1917. Serial No. 175,448.

To all whom it may concern:

Be it known that I, ALEXANDER S. SPIEGEL, a citizen of the United States, and resident of Chicago, Illinois, have invented certain new and useful Improvements in Apparatus for Producing Shingles, of which the following is a specification.

My invention relates to an apparatus for producing shingles of the composition type 10 very quickly and with a minimum amount of waste.

My invention aims to produce shingle strips or slabs out of a roll of fabric which is normally the depth of four strips and I 15 utilize mechanism for cutting out of this fabric positively a series of strips or slabs by operating on the roll laterally.

In the accompanying drawing:

The figure is a plan view showing my im- 20 proved form of die and die plate, and re- quiring the roll to be slit in four sections.

Referring to the figure of the drawing the roll is shown at *a* and is of the usual composition material and this is fed by feeding 25 mechanism of usual and ordinary construction, as shown at *b*, slitters being also driven by this mechanism as shown at *c'*, for slitting the fabric centrally. A die plate *d* re- ceives and supports the fabric as it passes 30 above it and as the mechanism is adapted to feed the fabric continuously, suitable dies *e'* supported on shafts *f* are adapted to be rotated in connection with the die plate to

die out a unit of the shape shown by the die leaving between the two dies two additional units, which by reason of the central slit are automatically produced at the same time that the marginal units are produced. After the dies have acted the fabric is fed along and the end die *g'* will cut off the central 35 units at the dotted line *h*, thus completing 40 four sections.

The laterally operating dies *e'* cut out the edge sections and cut out the slots of the center sections, the dies being recessed at *e''* 45 to form corresponding slots in the side sections. The only waste is in the portions of the fabric within the slotted sections *e''* of the dies and that made by cutting the slots of the center sections. 50

What I claim is:

In combination with a roll supporting the fabric, feeding means for the fabric, means for slitting the fabric into longitudinal outer and central sections, a die plate over which 55 the fabric passes and laterally operating dies comprising main sections having recesses *e''* and portions adapted to form slots in the central sections and a cutter for severing the fabric transversely, substantially as 60 described.

ALEXANDER S. SPIEGEL.
